DIE HEAD

Otto Hoelzel, New Haven, Conn., assignor to The
Eastern Machine Screw Corporation, New
Haven, Conn., a corporation of Connecticut

Application January 14, 1935, Serial No. 1,771

15 Claims. (Cl. 10—120.5)

My invention relates to die heads and while, more particularly, it relates to die heads for cutting taper threads, many of its features are applicable to die heads for cutting straight threads.

Under present commercial practice, it is customary to employ chasers having taper cutting edges to cut taper threads and the taper of the chaser controls and determines the taper of the threads. The cutting of taper threads in this manner is objectionable because, instead of only the forward or leading teeth of the chasers doing the cutting, as is usual in cutting straight threads, substantially all of the teeth (the number depending upon the number of threads being cut) of each chaser join in the cutting operation. This not only throws a great strain on the teeth behind the forward or leading teeth, but, due to the fact that the chasers make a broad cut, each of them, where it stops cutting, leaves a shallow shoulder extending transversely of the threads. Moreover, by having the chasers make a broad cut, there is a tendency to break teeth out of the chasers and the power required to make such a cut is considerably greater than required when the cutting is confined to the leading teeth. Another and important objection to cutting taper threads in this manner is that the taper depends entirely upon the accuracy of the taper originally given to the chasers.

The principal object of the present invention is to provide a die head with simple and improved means for cutting taper threads by gradually moving the chasers, whereby the same free cutting action is obtained as when cutting straight threads.

Another object of the invention is to provide improved means for automatically causing the chasers to move into inoperative positions, after the desired number of threads have been cut.

A further object of the invention is to provide a die head with improved means for chamfering the end of the work being threaded.

A primary feature of the invention consists in providing a die head with rectilinearly movable means cooperable with the chasers for moving them with respect to the body member on which they are mounted for cutting taper threads and in combining therewith relatively rotatable means for controlling the movement of the rectilinearly movable means.

Another feature of the invention consists in providing the die head with axially movable means adapted to be operated by the work be-

ing cut for actuating mechanism controlling the movement of the chasers.

Another and more specific feature of the invention consists in providing a die head having a body member and a shank extending rearwardly therefrom with means movable longitudinally of the shank for actuating the chasers which are movably mounted on the body member and with means encircling the shank and rotatable relatively thereto for controlling movement of the movable means.

A further feature of the invention consists in providing a die head with movable means engageable by the work being threaded for operating the mechanism controlling movement of the chasers, the movable means being provided with spring pressed means for chamfering the end of the work being threaded.

Other and more specific features of the invention, residing in advantageous forms, combinations and relations of parts, will hereinafter appear and be pointed out in the claims.

In the drawings, illustrating a preferred embodiment of the invention,

Figure 1 is a side elevational view of the die head, with parts thereof broken away, showing the head in closed or operative position.

Figure 2 is a view similar to Figure 1, additional parts of the head being broken away, showing the head in open or inoperative position.

Figure 3 is a longitudinal sectional view of the die head.

Figure 4 is an end view of the die head.

Figures 5 and 6 are sectional views taken on lines 5—5 and 6—6, respectively, of Figure 3.

Figure 7 is a side elevational view of the operating plunger.

Figure 8 is a side elevational view of the operating plunger taken at right angles to the view shown in Figure 7.

Figure 9 is a front end view of the operating plunger.

Figure 10 is a rear end view of the operating plunger.

Figure 11 is a sectional view taken on line 11—11 of Figure 7.

Figure 12 is a detail view of one of the lugs or shoes of the operating plunger.

Figure 13 is a fragmentary view partly in elevation and partly in section, the section being taken on a line corresponding to line 13 of Figure 6.

Figure 14 is a sectional view of the collar and cam ring.

Figure 15 is a side elevational view of the cam ring.

Figure 16 is a side elevational view of the sleeve to which the cam ring is secured.

5 Figure 17 is a front end view of the sleeve shown in Figure 16.

Figure 18 is an elevational view of the ring disposed within the chaser actuating collar.

10 Figure 19 is a fragmentary end view of the collar.

Figure 20 is a side elevation of one of the carriers and its associated chaser.

15 Figure 21 is a fragmentary sectional view taken on a line corresponding to line 6—6 of Figure 3 of a modified form of the invention.

20 Referring more particularly to the drawings, 1 designates the body member of the die head which is provided with a rearwardly extending tubular shank 2 for connecting the head to any 25 suitable machine. The front face of the body member is formed with a plurality of grooves 3 for receiving carriers 4 for the chasers 5. The grooves 3 intersect the axial work or stock receiving opening 6 of the head and they are preferably disposed radially with respect to the opening. The chasers 5 are preferably of the type disclosed and claimed in the Warren Patent No. 1,937,418 dated November 28, 1933, each being immovably secured to its carrier by a locking 30 screw 7.

35 The front or leading side of each carrier is provided with an inclined recess 8 for receiving means to be hereinafter described adapted to move the carrier toward and away from the work receiving opening.

40 The carriers are retained in the grooves 3 by segmental plates 9 secured to the front face of the body member 1 and they are respectively provided with portions adapted to extend into grooves or recesses 10 formed in the front or leading side of the carriers.

45 Encircling the shank 2 and movable longitudinally thereof is a collar 11 having forwardly projecting pins or studs 12 which are adapted to extend into openings in the body member 1 communicating with the carrier receiving grooves 3. The forward end of each of the pins 13 has a laterally projecting inclined lug 13 for cooperating 50 with the inclined recess 8 in the adjacent carrier. As the recesses 8 of the carriers are inclined with respect to the axis of the head, it will be appreciated that, when the collar 11 is moved axially thereof, the carriers and consequently the chasers will be moved either toward or 55 away from the axis, depending upon the direction of movement of the collar with respect to the body member.

60 Operatively interposed between the collar and head are a plurality of springs 14 normally tending to move the collar rearwardly with respect to the head. The springs are preferably disposed within oppositely arranged recesses in the head and collar and, to prevent them from collapsing laterally, centering pins 15 which extend rearwardly from the head into the springs may 65 be conveniently employed.

70 Encircling the shank 2 and extending between the latter and the collar 11 is a sleeve 16 which is relatively rotatable with respect to both the shank and collar. Adjacent its inner end, the sleeve is provided with diametrically opposed forwardly extending lugs 17, each of which is provided on one side with a step portion to provide a shoulder 18. The lugs 17 are preferably formed 75 integrally with a circumferentially adjustable

ring 19 which is secured to the sleeve 16 at the inner end thereof. To prevent relative circumferential movement between the sleeve 16 and ring 19, after these parts have been adjusted in the desired position, the inner end of the ring is serrated, as indicated at 21, for cooperating with serrated portions provided on the front face of an outwardly projecting annular flange 22 which may be advantageously formed integral with the inner end of the sleeve. Relative axial 10 movement of the ring and sleeve may be conveniently prevented by two screws 23, the inner ends of which are adapted to extend within a circumferential groove 24 formed in the exterior surface of the sleeve closely adjacent the annular flange 22.

15 While the sleeve 16 and the ring 19 are relatively rotatable with respect to the shank 2, means is provided for locking these parts against relative axial or longitudinal movement. This 20 means comprises a split nut 25 which is preferably made in two semi-circular sections, the inner surfaces of which are threaded to cooperate with screw threads 26 formed on the exterior of the shank. Each section of the split nut has a 25 forwardly extending annular portion 27, the inner surface of which is formed with a groove for receiving a rib or fin 28 projecting outwardly from the annular flange 22 of the sleeve 16. The split nut is maintained in assembled position by 30 two screws 29, which may be tightened sufficiently to rigidly clamp the nut to the shank. When in clamping engagement with the shank, the nut prevents relative longitudinal movement between the shank and sleeve, but sufficient clearance is 35 provided between the cooperating portions of the nut and sleeve to enable the latter to rotate relatively to the nut and consequently also the shank.

30 The forward ends of the lugs 17 on the ring 19 are inclined, as shown at 30, with respect to the 40 longitudinal axis of the head and they are adapted to cooperate with the collar 11 for restraining the latter from moving rearwardly under the influence of springs 14. Instead of having the lugs 17 engage the collar itself, it is preferred to 45 have them engage a circumferentially adjustable ring 31 which is disposed within an annular recess formed in the rear face of the collar. This ring, which is shown in detail in Figure 18, is retained in assembled relation with the collar by 50 lugs 32 which project inwardly into the recess formed in the rear face of the collar and overlap portions of the outer face of the ring. To enable the ring to be readily assembled with and disassembled from the collar, it is provided on its outer 55 side with recesses or notches 33 of sufficient length to receive the lugs 32. In assembling the ring with the collar, the ring is positioned so that the notches 33 are opposite the lugs 32, at which time the ring may be moved into the recess of the collar and then subsequently rotated, so that the lugs will overlap portions of the ring on opposite sides of the notches. The inner surface of the ring 31 is also provided with notches or recesses 34, which, in addition to affording shoulders, 35 60 with which the inclined ends 30 of the lugs 17 are adapted to engage, provide spaces into which the lugs 17 may project after the latter have been moved from engagement with the shoulders 35. The inner end of the recess of the collar in which 65 the ring 31 is disposed is preferably additionally recessed, as indicated at 36, adjacent the notches 34 of the ring.

65 Means in the form of a plunger which is movable within the shank 2 and is adapted to be actu- 70 75

ated by the work as threads are being cut thereon is preferably employed for rotating the cam ring 19. The plunger comprises a hollow cylindrical body portion 37 having a removable extension 38, the forward end 39 of which is of reduced cross sectional area and has a front face 40 affording an abutment adapted to be engaged by the work during the thread cutting operation. Portion 39 of the extension is preferably of substantially 10 cruciform shape in cross section to provide spaces into which the chasers may, if necessary, extend. The extension 38 extends rearwardly into the body portion 37 of the plunger, being locked against relative rotation thereto by a key 39a, and it terminates in a threaded stud 41 for receiving a nut 42 for rigidly connecting the extension to the body. The plunger is provided with oppositely projecting removable shoes or the like 43 having reduced inner end portions 44 extending 20 within openings in the body portion 37 and enlarged flattened portions 45 projecting into longitudinally extending slots 46 in the shank 2. The outer ends of each of the shoes is formed with an inclined head or lug 47 which extends into a steeply inclined spiral groove 48 in the inner surface of sleeve 16. The plunger is normally urged forwardly within the spindle by a helical spring 49, one end of which bears against a shoulder within the plunger and the other end of which bears 30 against an annular shoulder 50 projecting into the bore of the spindle.

The outer end of extension 38 is provided with a transverse groove 51 for receiving a chamfering tool 52. This tool is formed with inwardly converging cutting edges 53 adapted to cooperate with the exterior of the work being threaded for chamfering the outer side of the adjacent end thereof and it is also provided with a nub or the like 54 extending forwardly between the cutting edges 53 and having cutting edges 55 for chamfering or reaming the inner side of the work being threaded.

The chamfering tool is loosely connected to the operating plunger so that it may move longitudinally with respect thereto and also transversely thereof, the latter movement enabling the tool to adjust itself to the work and thereby cut evenly. This loose connection between the chamfering tool and the plunger may be advantageously accomplished by providing the tool with an elongated slot 56 for receiving a screw or the like 57 which extends transversely of the groove 51, the diameter of the screw being somewhat less than the width of the slot.

The screw 57 and slot 56 are so related that, when the chamfering tool is moved forwardly with respect to the operating plunger, the inner end of the slot engages the screw, but, when the tool is moved rearwardly with respect to the plunger, its inner end engages the bottom or end 58 of the groove 51 in which the tool is disposed. The inner end of the chamfering tool is normally maintained in spaced relation to the bottom 58 of groove 51 by a spring pressed pin 59 which extends through a bore in the extension 38 and terminates in a shouldered head 60 adapted to cooperate with the inner end of the extension. A spring 61, which is disposed within a cylindrical extension 62 of nut 42, bears against the head 60, thus urging the pin forwardly to cause its outer end to engage the inner end of the chamfering tool and thereby normally maintaining the latter in spaced relation to the bottom of the groove 51.

The chamfering tool is normally disposed in 75 such a position that it will not operatively cooper-

ate with the inner end of the work until two or three threads have been cut and the outer face of the forward end 39 of the extension against which the work is adapted to abut is so related or positioned with respect to the chasers that the work will not engage it until three or four threads have been cut. Although the chamfering tool is arranged so that it will be engaged by the work before the abutment, the work may engage the abutment without the chamfering tool necessarily performing any of its cutting function, because the tool may recede or move inwardly relatively to the plunger by compressing the spring 61. However, the spring 61 and the pin 60 maintain the chamfering tool in engagement with the work and the tool will continue to gradually cut until its relative forward movement is arrested by the inner end of the slot 56 engaging the screw 57. Under ordinary conditions, however, the chamfering tool will have completed its cutting 20 operation by the time the work engages the abutment of the plunger. By loosely connecting the chamfering tool with the operating plunger, it will be perceived that not only will the tool readily adjust itself to the pipe or the like being 25 threaded, but, should a split develop in the pipe, as sometimes occurs, the tool will not be damaged as it may move inwardly into the plunger. Moreover, as the work being threaded cooperates directly with the plunger itself and not with the 30 chamfering tool for causing the plunger to move inwardly for operating the die head, the chamfering tool is not subjected to excessive strains as would be the case if the force for operating the plunger was transmitted therethrough. 35

In the operation of the die head, the parts are generally in the position illustrated in Figure 1. The die head may be caused to rotate as a whole with respect to the work or the work may be caused to rotate with respect to the head. Upon 40 relative rotation of the head and the work, two or three threads will be cut before engagement of the chamfering tool and work and, after one or two more threads are cut, the work engages the outer end of the operating plunger. As stated 45 before, the chamfering may occur before the work and plunger engage or it may continue after this time. As the thread cutting operation continues, the plunger in contact with the end of the work is moved inwardly relatively to the 50 head, thus causing rotation of the sleeve 16 by means of the shoes 43 riding in the spiral grooves 48 on the inner surface of the sleeve. The cam ring 19 being rigidly secured to the sleeve rotates therewith relatively to the collar 11 and its 55 associated ring 31. During rotation of the sleeve, the cam or incline surfaces of the lugs 17 move along the cooperating shoulders 35 of ring 31, thus enabling the collar 11 under the influence of springs 14 to move rearwardly slowly with respect to the body 1. As this occurs, the chasers are gradually retracted by the lugs 13 on the studs 12 carried by the collar working in the inclined recesses 8 in the sides of the chaser carriers. Gradual retraction of the chasers will, 60 of course, produce the desired taper threads and, since the rate at which the chasers are retracted determines the amount of taper, any desired taper may be formed by varying the inclination of the 65 forward ends of lugs 17. 70

Although it is preferred to employ chasers having a taper corresponding to the taper of the threads to be cut, such chasers are merely used so that the rear teeth can control the longitudinal 75

movement of the die head or work in accordance with the pitch of the thread.

As the relative rotation between the cam ring 19 and the collar 11 continues, the inclined forward ends of the lugs 17 pass from engagement with the shoulders 35, at which time the thread of the desired length has been cut and the collar is projected rapidly rearwardly by the springs 14, thus causing the chasers to move into inoperative position out of engagement with the work. The rapid rearward movement of the collar is arrested by the ring 31 engaging the shoulder 18 on the cam ring and, when the parts are in this position, the lugs 17 are disposed within the notches 34 or recesses 34 of ring 31. If desired, shoulder 18 may be formed with a forwardly projecting rib 63 which is adapted to extend within a groove 64 in ring 31 to arrest relative rotation between sleeve 16 and collar 11.

As the length of the thread being cut is determined by the amount of initial overlap between the cam lugs 17 and the shoulders 35, the length of the thread may be adjusted by varying the amount of this overlap. Two separate means are provided for this purpose, one for obtaining fine adjustment and the other for obtaining a comparatively coarse adjustment. The fine adjustment is obtained by rotating the ring 31 relatively to the collar and the coarse adjustment is obtained by shifting the ring 19 circumferentially of the sleeve 16.

While any suitable means may be provided for rotatably adjusting the ring 31, it is preferred to employ a worm 65 which is rotatably mounted in the collar 11 and is adapted to cooperate with a gear sector 66 formed on the outer surface of the ring 31 within one of the recesses 33 thereof. The worm 65 may be conveniently formed on a rod, one end of which has an enlarged cylindrical head 67 journaled within an opening 68 of the collar and the other end 69 of which is of reduced diameter and is screw threaded to receive a nut 70, the nut being journaled in an opening 71 formed in the collar in alignment with opening 68. The inner end of nut 70 is adapted to bear against a shoulder 72 in the collar, so that the worm may be firmly locked against rotation. When it is desired to actuate the worm for rotatting ring 31 into a new position of adjustment, it is only necessary to back off nut 70, then rotate the worm, after which the nut may again be tightened to secure the ring in its new position of adjustment. It will thus be observed that ring 31 may be easily and quickly shifted relatively to collar 11 so as to initially vary the amount of overlap between the ring and lug 17, whereby a very fine adjustment for the length of thread is obtained.

Instead of employing a worm 65 for rotatably adjusting the ring 31, two opposed screws 73 may be used, as illustrated in Figure 21. The screws are disposed within threaded openings 74 in the collar 11' and, at their inner ends, they cooperate with a lug 75 which projects radially from the ring 31' and is preferably formed integrally therewith. Except for the lug 75, ring 31' corresponds in substantially all details with ring 31. It will be perceived that ring 31' may be readily and quickly rotated into a new position of adjustment by simply backing off one screw 73 and tightening the other one.

To obtain a coarse adjustment for the length of thread, it is merely necessary to loosen binding screws 23 and, with the die head closed as much as possible (that is, with the collar moved

forwardly with respect to the body member 1 out of engagement with the lugs 17), disengage the notched or serrated portions of ring 19 and sleeve 16 by moving the ring forward slightly, rotate the ring relatively to the sleeve the desired amount, then move it rearwardly to cause the serrated portions to again cooperate, after which the binding screws may be tightened and the ring thus secured in a new position of adjustment.

The die head may be adjusted to cooperate with work or stock of different diameters by shifting the sleeve 16 and consequently the ring 19 longitudinally of the shank 2. This may be easily accomplished by slightly loosening the screws 29 which clamp the split nut 25 to the shank to enable the split nut to be rotated relatively to the shank. Rotation of the split nut in one direction will cause the sleeve 16 and cam ring 19 and consequently collar 11 to move forwardly relatively to the body member 1 and thus move the chasers 20 inwardly for cooperating with work of relatively small diameter, while rotation of the split nut in the opposite direction will cause movement of the sleeve and cam ring and consequently the collar 11 away from the body member and thus position the chasers to cooperate with work of larger diameter. After the split nut has been properly adjusted, the screws are then tightened to clamp it rigidly to the shank and thus prevent longitudinal shifting of the sleeve 16 and cam 30 ring 19 relatively to the shank.

From the foregoing, it will be perceived that efficient and comparatively simple means have been devised for gradually moving the chasers to cut taper threads and that the mechanism for actuating the chasers includes means for effectively chamfering the end of the work being threaded.

What I claim is:

1. In a die head, the combination with a body member having a work receiving opening, of chasers movably mounted on said body member, and mechanism for gradually moving said chasers transversely of the axis of said opening for cutting taper threads, said mechanism including means movable axially of said opening for actuating the chasers, spring means normally tending to move said movable means, means relatively rotatable with respect to said movable means for permitting gradual movement of the latter by said spring means during the cutting of a plurality of threads whereby said chasers are actuated to cut taper threads, and means for effecting gradual rotation of said rotatable means during the cutting operation. 55

2. In a die head, the combination with a body member, of chasers movably mounted on said body member, mechanism for gradually moving said chasers with respect to said body member to cut taper threads, said mechanism involving rectilinearly movable means cooperable with the chasers for moving the latter, spring means normally tending to move said movable means, means cooperable with said movable means and relatively rotatable with respect thereto for permitting gradual movement of said movable means by said spring means during the cutting of a plurality of threads, and means operated by the work being cut for gradually actuating said rotatable means during the thread cutting operation. 70

3. In a die head, the combination with a body member having a work receiving opening and provided with a rearwardly extending shank, of thread cutting chasers movably mounted on said 75

body member, spring actuated means cooperable with the chasers for moving the latter to cut taper threads, rotatable means having wedging engagement with said spring actuated means normally preventing the latter from moving the chasers to inoperative position, means slideable within said opening and operated by the work being cut for causing gradual movement of said rotatable means to permit the spring actuated means to gradually move the chasers, and spring means disposed within said shank and cooperable with the slideable means for returning said rotatable means to normal position.

4. In a die head, the combination with a body member having a work receiving opening, of chasers movably mounted on said body member, mechanism for gradually moving said chasers transversely of the axis of said opening for cutting taper threads, said mechanism including means movable axially of said opening for actuating the chasers, spring means normally tending to move said movable means, means relatively rotatable with respect to said movable means for permitting gradual movement of the latter by said spring means during the cutting of a plurality of threads, and means movable within the opening and actuated by the work being threaded for causing said rotatable means to gradually rotate during the cutting of said plurality of threads.

5. In a die head, the combination with a body member having a work receiving opening, of a plurality of chasers movably mounted on said body member, means movable axially of said opening for moving the chasers transversely of the axis of said opening, spring means for actuating said movable means, means relatively rotatable with respect to said movable means normally restraining movement thereof by said spring means, said rotatable means and said movable means respectively having engaging portions one of which is inclined to the axis of said opening whereby upon relative rotation of said means said movable means is permitted to move axially of the opening to cause gradual movement of said chasers for cutting taper threads, and means actuated by the work being threaded for gradually rotating said rotatable means during the threading operation.

50 6. In a die head, the combination with a body member having a rearwardly extending shank, of chasers movably mounted on said body member, means movable longitudinally of the shank cooperable with said chasers for actuating the latter, means rotatable relatively to said movable means encircling said shank, said rotatable means having a cam surface cooperable with said movable means for permitting the latter to move during the cutting of a plurality of threads so as to cause gradual movement of the chasers for the cutting of taper threads, and means engageable by the work for gradually rotating said rotatable means during the cutting of said plurality of threads.

65 7. In a die head, the combination with a body member having a rearwardly extending shank, of chasers movably mounted on said body member, means movable longitudinally of the shank for moving the chasers relatively to the body member, a sleeve rotatable relatively to said means encircling the shank, and a ring secured to said sleeve and having a cam surface cooperable with said means for controlling movement of the latter to cause gradual movement of the chasers for cutting taper threads, said ring being rotatably

adjustable on said sleeve to regulate the length of thread to be cut.

8. In a die head, the combination with a body member having a rearwardly extending shank, of chasers movably mounted on said body member, mechanism for moving said chasers relatively to the body member, said mechanism including a collar movable longitudinally of the shank, a sleeve encircling the shank between the latter and the collar and being rotatable relatively to the collar, a ring circumferentially adjustable on the sleeve having a portion engageable with the collar for controlling movement of the latter, and means movable within said shank for rotat-
ing the sleeve.

15 9. In a die head, the combination with a body member having a rearwardly extending shank, of chasers movably mounted on the body member, means for moving said chasers involving a rotatable sleeve encircling said shank and having a cam groove on its inner face, an axially movable collar encircling said sleeve and having portions cooperable with the chasers, a ring circumferentially adjustable on the sleeve having portions engageable with the collar, and a plunger mov-
able within said shank having a portion disposed within said cam groove for rotating the sleeve and ring for controlling movement of said collar.

20 10. In a die head, the combination with a body member having a rearwardly extending shank, of chasers movably mounted on the body member, means movable longitudinally of the shank for moving the chasers relatively to the body member for cutting taper threads, means rotat-
ably mounted on the shank for controlling move-
ment of said movable means, said rotatable means being movable longitudinally of the shank to assume different positions of adjustment, and means adapted to overlappingly engage opposite sides of a portion of said rotatable means for se-
curing the latter in a desired position of adjust-
ment against movement longitudinally of the shank.

25 11. In a die head, the combination with a body member having a rearwardly extending shank, of chasers movably mounted on said body member, a collar member movable longitudinally of the shank for gradually moving the chasers relatively to the body member for cutting taper threads, said collar member having a rotatably
adjustable ring and being provided with portions overlappingly engaging opposite sides of the ring preventing the ring from moving axially relatively to the collar, and means encircling the shank rotatable relatively to said collar and having a portion engageable with said ring for controlling movement of said collar.

30 12. In a die head, the combination with a body member having a rearwardly extending shank, of chasers movably mounted on the said body member, a collar member movable longitudinally of the shank and having means cooperable with said chasers for moving the latter relatively to the body member, said collar having a ring ro-
tatably adjustable with respect thereto, means carried by the collar for rotating said ring, and means encircling the shank relatively rotatable with respect to the ring, said encircling means having a member circumferentially adjustable thereon adapted to engage the ring for controlling movement of said collar member.

35 13. In a die head, the combination with a body member having a work receiving opening, of chasers movably mounted on said body member, mechanism for moving said chasers relative to

the body member, means for actuating said mechanism, said means including an abutment engageable by the work being threaded, and a chamfering tool normally disposed in advance of said abutment, said tool being movable with respect to said means to enable the work to engage said abutment.

14. In a die head, the combination with a body member having a work receiving opening, of 5 chasers movably mounted on said body member, mechanism for moving said chasers relative to the body member, means operable by the work being threaded for actuating said mechanism, said means having an abutment engageable by 10 the work, a chamfering tool slidably mounted on said means adjacent the forward end thereof and normally disposed in advance of said abutment, and spring means enabling said tool to

recede with respect to said means during the threading operation and for yieldably maintaining the tool in engagement with the work.

15. In a die head, the combination with a body member having a work receiving opening, of 5 chasers movably mounted on the body member, mechanism for moving the chasers relative to the body member, movable means extending within the opening and operable by the work being threaded for actuating said mechanism, said 10 means including an abutment engageable by the work, spring means opposing movement of said movable means, a chamfering tool movably mounted on said movable means, and yieldable means normally maintaining said tool in advance 15 of said abutment.

OTTO HOELZEL.
